UNITED STATES PATENT OFFICE.

MILVERN J. MORFORD AND GEORGE E. AMBROSE, OF SKIDMORE, MISSOURI.

VERMIN-EXTERMINATOR.

SPECIFICATION forming part of Letters Patent No. 698,723, dated April 29, 1902.

Application filed February 12, 1902. Serial No. 93,768. (No model.)

To all whom it may concern:

Be it known that we, MILVERN J. MORFORD and GEORGE E. AMBROSE, citizens of the United States, residing at Skidmore, in the 5 county of Nodaway and State of Missouri, have invented certain new and useful Improvements in Vermin-Exterminators, of which the following is a specification, reference being had therein to the accompanying 10 drawings.

Our invention relates to new and useful improvements in vermin-exterminators for poultry; and its object, among other things, is to provide a device of simple and inexpensive 15 construction which may be readily adjusted to hold motionless a fowl of any size during the operation of fumigation.

Another object is to employ novel means whereby the fowl is prevented from smothering during the operation.

With these and other objects in view the invention consists in the novel construction and combination of parts hereinafter more fully described and claimed, and illustrated 25 in the accompanying drawings, showing the preferred form of my invention, and in which—

Figure 1 is a perspective view of the device, showing the lid raised and a fowl in position. 30 Fig. 2 is a section on line 2 2, Fig. 3. Fig. 3 is a plan view with the lid removed. Fig. 4 is an end elevation. Fig. 5 is a similar view of the opposite end. Fig. 6 is an enlarged detail view of a portion of said end, showing the slide 35 raised and also showing in dotted lines said slide reversed; and Fig. 7 is a detail view of an adjusting-screw and showing the means for holding it in operative position.

Referring to the figures by characters of 40 reference, D is a box formed of any suitable material and having a lid K hinged to one side thereof. One end of the box is slotted downward from its upper edge, and the sides or edges of the slot are beveled on opposite sides, 45 as shown at G, thereby forming guides for a slide C, mounted in the slot. This slide is provided at one side of the center with an upwardly-extending slot E, covered by a sheet of rubber or other elastic material I, having an 50 aperture e' therein.

Slidably mounted in the box D are two vertical strips B B', arranged at right angles to

each other. To the inner and outer face of each strip is secured a metal plate f and e, respectively, each of which has an aperture registering with an aperture in the strip. Swiveled within these apertures is the upset end g of a screw b. This screw engages and projects through an internally-threaded sleeve c, fitted within the side of the box and secured thereto in any suitable manner, as by means of a collar d. Each screw b has a head A, which can be readily gripped by the fingers when it is desired to adjust the strip.

One end of the lid K is preferably cut away, 65 as shown at H, so as to permit the slide C to be raised when the cover is down upon the box. A suitable hasp I and staple M or other desired means may be employed for locking the lid when closed.

In operation a fowl is placed in the box between the sides and the strips B and B'. Said strips are then adjusted inward until the fowl is held practically against movement. Slide C is slid upward, if necessary, until the aperture e' is in alignment with the head, and said head is then thrust therethrough, the elastic fitting snugly about the neck. By reversing the slide, as shown in dotted lines in Fig. 6, the aperture e' can be brought nearer 80 the center of the end of the box. This is advantageous where very large fowls are placed in the device. After the fowl has been placed as above described a fumigator is put in the box and the lid closed. It will be seen that 85 the fowl will not suffer from suffocation during the fumigating process and is securely held against struggling.

In the foregoing description we have shown the preferred form of our invention; but we 90 do not limit ourselves thereto, as we are aware that modifications may be made therein without departing from the spirit or sacrificing the advantages thereof, and we therefore reserve the right to make such changes as 95 fairly fall within the scope of our invention.

Having thus fully described our invention, what we therefore claim as new, and desire to secure by Letters Patent, is—

1. The combination with a receptacle having a slot in one end thereof; of an elastic covering for said slot having a head-receiving aperture therein.

2. The combination with a receptacle hav-

ing a slot in one end; of a slide in said slot and having a slot therein, and an elastic covering for the slot in the slide, said covering having a head-receiving aperture.

5. The combination with a receptacle having a slot in one end; of a slide mounted in said slot and having a slot therein, a flexible covering to the slot in the slide and having an aperture therein adjustable to the neck of

10 a fowl.

4. The combination with a receptacle having a slot in one end; of a reversible, slotted slide in said slot; and an elastic covering for the slot in the slide, said covering having a 15 head-receiving aperture.

5.. The combination with a receptacle; of holding - strips slidably mounted therein, means for adjusting said strips at right angles to each other, a reversible, slotted slide mounted in a slot in the receptacle, and an 20 elastic covering to the slot in the slide, said covering having a head-receiving aperture.

In testimony whereof we affix our signatures in presence of two witnesses.

MILVERN J. MORFORD.
GEORGE E. AMBROSE.
